UNITED STATES PATENT OFFICE.

CLAUDE A. HERMAN, OF BRIDGEPORT, CONNECTICUT.

POWER-DRIVEN SCREWDRIVER.

1,394,089.

Specification of Letters Patent.

Patented Oct. 18, 1921.

Application filed October 1, 1919. Serial No. 327,782.

To all whom it may concern:

Be it known that I, CLAUDE A. HERMAN, a citizen of the United States, and resident of Bridgeport in the county of Fairfield and 5 State of Connecticut, have invented certain new and useful Improvements in Power-Driven Screwdrivers, of which the following is a specification.

This invention relates to new and useful 10 improvements in portable power-driven friction screw drivers, such as are used for driving screws, after being positioned, and whereby the screws are permitted to automatically stop rotating as soon as they are 15 driven home.

The purpose of the invention is to provide 20 a simple, compact and reliable form of instrument of the above class which may be connected to be driven with a flexible shaft and used within the radius of the length 25 of the shaft, for driving screws into machines or parts thereof, and so that the screw can be tightly driven home without damaging the screw or parts in which it is driven. 30 Further to so construct the device that the rotation of the screw will automatically stop under excessive resistance such for instance as when the head is set against the face of the object in which the screw is driven. 35 With these and other objects in view the invention resides and consists in the construction and novel combination and arrangement of parts hereinafter more fully described, illustrated in the accompanying 40 drawings, and pointed out in the claims hereto appended, it being understood that various changes in the form, proportion, size and minor details of construction within the scope of the claims may be resorted to 45 without departure from the spirit or sacrificing any of the advantages of the invention.

Similar characters of reference denote like or corresponding parts throughout the several figures of the accompanying drawings forming a part of this specification, and upon which,

Figure 1 shows a central longitudinal section through my improved form of screw 50 driver complete.

Fig. 2 is a longitudinal sectional elevation of the same showing the screw driver in its normal or inoperative position.

Fig. 3 is a cross section taken on line 3—3 55 of Fig. 2.

Fig. 4 is a detached end view of the inner

end portion of the driven spindle and the washer mounted thereon.

Fig. 5 shows a detached inner end view of the hand piece, the driving spindle and 60 split friction bushing mounted therein.

Fig. 6 shows a longitudinal view of a modified form of screw driver having an integral handle for turning the tool in the final tightening of a screw, and 65

Fig. 7 shows a cross section taken on line 7—7 of Fig. 6, to further illustrate the purpose of the handle and ratchet mechanism.

Referring in detail to the characters of reference marked upon the drawings, 6 70 represents a cylindrical hand piece which preferably has a reduced upper end portion in which a sleeve 7 is threadably attached. A recess 8 is formed in the sleeve to receive the flexible shaft 10 and its casing 9. The 75 detachable end of this shaft is in the form of a plug 11 that is shoved through the sleeve and positioned in the socket 12 and has one side cut away to engage a pin 13 in the spindle 14. The two end bearing portions of 80 this spindle are journaled and rotate in the cylindrical hand piece 6 and are adapted to be continuously operated through the flexible shaft connected thereto. The lower end portion 15 of this spindle is provided with 85 a cylindrical pocket 16 to receive the split friction bushing 17 and whose outer peripheral surfaces are shaped to snugly fit the inner walls of the pocket 16 and whose inner walls are conical shaped to receive the 90 correspondingly shaped end 18 of the driven spindle 19. This end portion of the shank is provided with a key 20 that extends cross-wise and projects from the opposite sides to engage the pockets 21 formed between the 95 adjacent walls of the two friction members so as to form an operative connection between the friction bushings and the shank in addition to the frictional engagement of the tapered end of the shank and the conical 100 walls of the bushing when the shank of the spindle is pressed up into the bushing.

A threaded closure cap 22 is screwed in the lower end of the handle portion and is locked in said position by a set screw 23. 105 This closure cap includes a cylindrical chamber of a lesser diameter than that of the hand piece and the inner end of the cap may form an annular shoulder 24 against which the washer 25 is positioned, the opposite side of the washer being similarly engaged by the annular shoulder in the
